UNITED STATES PATENT OFFICE

HENRY L. ARSTE, OF ALHAMBRA, CALIFORNIA

DOORKNOB LOCK

Application filed March 11, 1931. Serial No. 521,658.

My invention pertains to a door knob lock of a type in which the outer knob is provided with a lock and the inner knob is provided with a device for either locking or 5 unlocking the latch bolt.

In this type of lock an object and feature of my invention is the employment of a rotatable device connected to the inner knob whereby on actuation of the rotatable device the latch bolt may be locked or unlocked. 10 In this feature my present application distinguishes from my Patent No. 1,876,576, filed January 8, 1930, for a door knob lock, as, in the prior case the control by the inner knob 15 was through the medium of a slidable control means operated by a push bottom.

A further object and feature of my invention is the employment of a rotatable bottom or other finger grip device mounted in the 20 inner knob which on its actuation controls the operation of a rotatable detent in one case and a slidable detent in another instance or form of my invention, and on the relative positioning of the detent in relation to its 25 slidable crosshead the latch bolt is controlled in its movement.

By this construction the rotation of the finger grip button by moving the detent from its locking to its unlocking position allows the crosshead to be operated by the inner knob and also by this construction when the detent is placed in a locking position due to manipulation of the finger grip button on the inside or the lock in the outer knob, this usually being a barrel lock, the outer knob also 25 cannot be turned, but on release of the detent, through manipulation of the rotatable button grip on the inside or by the barrel lock on the outside either knob can be operated to open the door.

Another feature of my invention pertains to the detailed construction of the crosshead, this being formed in the present case of two metal structures die pressed into proper shape, such members fitting together and forming a structure which may be made by simple die pressing work.

Other features of my invention relate to the manner of securing the assembly of the door knob shanks or stems and the attach-

ment of the rosettes to such stems. Other detail features of my invention will appear from the following description taken together with the claims.

55

In the drawings:

Fig. 1 is a longitudinal section through a simplified form of a lock taken on the line 1—1 of Fig. 2 in the direction of the arrows with the latch bolt unlocked;

Fig. 2 is a transverse section on the line 2—2 of Fig. 1 in the direction of the arrows;

Fig. 3 is a similar section with the latch bolt locked;

Fig. 4 is an assembly of the detent and its operating connections;

Fig. 5 is an assembly of part of the knobs and knob shank structures;

Fig. 6 is a sleeve utilized with the assembly of Fig. 5;

Fig. 7 is an assembly of part of the rosette attachment and of the knob shank;

Fig. 8 is a perspective view of a centering and guide plate;

Fig. 9 is a longitudinal section of a modified construction of lock on the line 9—9 of Fig. 10 in the direction of the arrows;

Fig. 10 is a longitudinal section on the line 10—10 of Fig. 9 in the direction of the arrows;

Fig. 11 is a perspective view of a centering and guide plate;

Fig. 12 is a perspective view of an operating disk for actuating the slidable crosshead;

Fig. 13 is a perspective view of the slidable crosshead;

Fig. 14 is a perspective view of a driving cam;

Fig. 15 is a perspective view of a driven cam;

Fig. 16 is a perspective view of a detent;

90

Fig. 17 is a perspective view of a trigger;

Fig. 18 is a detail elevation of the trigger and detent assembly;

Fig. 19 is an assembly of the pulling cam for the outer knob lock;

95

Fig. 20 is an elevation of the pulling cam;

Fig. 21 is a perspective view of the trigger operating sleeve partly broken away.

Referring first to the construction of the lock illustrated in Figs. 1, 2, and 3, in this

100

- case the door is indicated by the numeral 11 and in an opening in this door there is fitted a sleeve 12 and in this sleeve there are a pair of guide plates 13, these plates being held in place by end pieces 14 on one side and the rosette 15 on the outer side of the door on the opposite side. The guide plates (note Fig. 8) are formed circular and have a circular slot 16 and have a radial guide 17 formed by perforating the plates as indicated at 19 and bending flanges 20 inwardly.
- 10

The crosshead construction which slides in these guides designated generally by the numeral 21 and illustrated in Fig. 3 comprises an outer and an inner member 22 and 23. The outer member has a top plate 24, two sides arms 25, these having inwardly bent ends 26. The inner member has a bottom plate 27, angular sections 28 and side strips 29 which fit 15 inside the sides 25 from which extend side pieces 30 which are pressed against the edges of the top plate 24. This construction of crosshead may be made entirely by die pressed elements secured together.

20

25 The latch bolt assembly utilizes a sleeve 31 which has a screw threaded connection 32 to the sleeve 12. An inner guide sleeve 33 guides the bolt head 34, this bolt head having a latch bolt 35, which is secured in a socket stud 36, this latter being attached to the plate 27 of the crosshead. A compression spring 37 bears on the plate 24 of the crosshead, this having a slightly upwardly bulged part 38 centering the spring. The tendency of the 30 spring is to always thrust the latch bolt outwardly and the locking of the lock is done by preventing inward movement of this crosshead.

35

40 The knob attachment on the inside of the lock employs the end piece 14 which has a central flange 39 (note Fig. 7) and this is provided with angle lugs 40, these having a portion 41 attached by rivets to the end piece 14 and having a spaced portion 42. In this 45 spaced portion there is fitted a spring 43, the spring being secured by the rivets underneath the portion 41. This gives a strong support and backing for the springs. The knob shank sleeve designated generally at 44 has a ring 45 with outwardly bent fingers 46. These fingers engage underneath the springs 43 and hold the assembly in place. The rosette 47 is secured to the shank 44 and thus is held securely against the door.

50

55 The inner knob 48 is indicated as having a glass portion 49 and a metal section 50 rigidly connected thereto and fitted in the metal section of the knob and the central opening. In the glass portion there is a plug 52, this plug having a central cylindrical portion 53 fitting in the socket 54 in the metal part 50. (Note Fig. 5.) A sleeve 54 fits on a small tubular portion 55 of the metal portion 50 of the knob, this latter being threaded 60 as indicated at 56 and with diametrically

65

opposite slots 57. (Note Fig. 5.) The sleeve 54 has a tubular section 58 and an enlarged head 59 with slots 60. This head is threaded internally as indicated at 61. With this construction the sleeve 54 may be secured to the metal part 50 of the knob by screw threading these together and with the slots 57 and 60 in alignment. The crosshead moving device cooperates with the handle and shank of the inner member by means of a disk 62 which has a tubular stem 63 connected thereto, this stem having splines 64 which fit in the notches 57 and 60. The disk is provided with a plurality of pins 65 which engage the lower edge of the side pieces 30 of the crosshead whereby on turning the knob in either one direction or the other these pins cause a retraction of the crosshead against the spring 37 and thereby withdrawal of the latch bolt. 70

75

80 The outer knob 66 operates in substantially the same manner, this knob having a shank 67 with a disk 68 rigidly secured thereto, this disk having a pair of pins 69. The pins on both of the disks operated by the knobs, as above mentioned, operate through the slots 16 in the end guide plates 13. The movement of the crosshead is guided between the flanges 20 on these guide plates. Such guide plates are prevented from turning and are rigidly secured to the sleeve 12 by means of fingers 70 which extend through perforations 71 in these plates. 85

90 The locking and unlocking mechanism for the construction of Figs. 1 to 3 employs a detent designated generally at 72 (note Fig. 4). This detent is formed of a metal bar 73 having a laterally extending finger 74, this having a pair of prongs 75. This finger 100 passes through the tubular hub 76 attached to one of the guide plates 13 (note Figs. 1, 8, and 11) and at the end 78 is secured to a cylindrical block 79, this block having a 105 kerf 80 therein, there being aligned pin holes 110 for attachment by a pin. The block 79 has a half cut sectional end 81 which engages with a similar half cut end 82 on an intermediate block 83. This latter block is provided with a transverse kerf 84 in which fits the tongue 115 85 of an outer block 86, this latter having the finger operated button or device 87. A screw 88 is utilized to attach the blocks 83 and 86 (note Fig. 1). A spring 89 (note Fig. 8) is secured to the outer end of the hub 76 of the guide disk. This spring has a concave bent section 90 and an end 91. The spring is so located as to normally tend to hold the detent in the unlocked position but when the detent is turned to the locked position it also retains the same in such locking engagement with the crosshead as hereinunder detailed. The detent is limited in its 120 rotational movement by the abutment shoulders 92 on the inner end of the hub 76 125

of the guide plate. (Note Figs. 1, 2, 3, and 11.)

At the outer knob end the detent is also connected to the lock, there being a barrel lock 93 illustrated as mounted in the outer knob, this barrel having a rotatable element 94, and connected to this there is a block 95 having a screw 96 forming a connection. This block has a half rabbeted end section 97 (note Figs. 1 and 4). This latter section engages a loose block 98 which also has a half rabbeted section 99 and is provided with a transverse kerf 100 engaging the end 101 of the detent, there being a pin 102 connecting the block 98 and the detent. By this construction by the use of a proper key in the outer knob the rotatable element of the lock may be turned, thus turning the block 95, the block 98, and the detent from the unlocked position of Fig. 2 to the locked position of Fig. 3, and in this locked position the finger 74 engages the plate 27 of the crosshead and thus holds this in its outermost position, thereby holding the latch bolt in the locked position. This action of locking the door through the outer lock rotates the thumb button 87 of the inner knob, and to unlock the lock from the inside it is only necessary to rotate this button in the opposite direction. This construction also allows the lock to be locked from the inside of the door by merely turning the thumb button 87 which, through the medium of the elements 86, 83, and 79, rotates the detent. In the construction of Figs. 1 and 2 the hub 103 on the guide plate adjacent the outer knob does not have the abutment shoulders as illustrated on the hub of the other plate as such is not necessary. It will be noted by this construction that the knob shank sleeve 44 is firmly attached to the sleeve 12 fitting in the door and holds the rosette 47 in a snug and tight position against the door.

In the construction of the lock illustrated in Figs. 9 and 10, the outer knob construction designated 120 has a shank 121 with a disk 122 rigidly secured thereto, this disk having pins 123 which operate through the arcuate slot in the guide plate. The lock 124 has a rotatable barrel 125 (note Figs. 9 and 19) provided with a pair of pins 126 which engage in sockets in a block 127. This block also has a pair of pins 128. The block 127 is secured to the barrel by means of screws 129 which engage through screw holes 130 in the block 127 and are threaded into the threaded holes 131 of the barrel. The pins 128 fit loosely in the sockets 132 in the cam block 133, this block having a pulling cam surface 134 on an arcuate cam finger 135, such pulling cam surface being constructed to pull on the sliding detent as hereinunder detailed. The finger 135 is also provided with a pushing cam surface 136 to push on the trigger as hereinunder detailed (note Figs. 19

and 20), this cam being operated by operation of the lock.

The inner knob 137 and its shank are substantially the same as the knob and shank illustrated in Fig. 1 in the principles of construction, the detail size being different. In this case a glass knob 138 has a metal part 139 secured thereto on the inside and a plug 140 on the outside. The metal section 139 has an exteriorly threaded tubular portion 141 over which is threaded a sleeve 142. The knob shank sleeve designated generally at 143 is substantially the same as the similar sleeve 44 of Fig. 1, the proportions being different but the connections by means of the springs 80 on the end pieces being the same as in the construction of Fig. 1.

The crosshead employed in this lock is illustrated in Fig. 13 and, in addition, there is provided a notch 144 in one of the side pieces 30 to engage an element on the sliding detent to lock the crosshead in its locking position.

In Figs. 9 and 10 the finger operating-button 144 has a shank 145 with a notch 146 thereon. This notch engages in a tongue on a block 147 and this block itself has a tongue and notch connection with a driving cam block 148 (note Fig. 14), this cam block having a cam surface 149 which is formed as a screw curvature. This cam block fits in the sleeve 150 (note Fig. 21), which sleeve has a head 151 at its inner end with a lug 152 extending from this head. The driving cam block fits inside of the sleeve 150 from its outer end and engages a driven cam 153. This driven cam has a projecting finger 154, which finger at the end rides on the cam surface 149. The driven cam has a slot 155 and is secured to the detent designated generally at 156 (note Fig. 16), this being secured to a pin hole 157 at one end. A helical compression spring 158 is fitted in the sleeve and bears against the inside of the head 151. This compression spring tends to retract the detent toward the inner knob and thus keep the finger 154 pressed against the cam surface 149 of the driving cam.

The detent 156 has a shank portion 159 with a notch 160 in one side and a laterally extending finger 161 on the opposite side. This finger is adapted to fit in the notch 144 in the side plate of the crosshead to prevent movement of such crosshead and thereby lock the latch bolt in its locking position. An end finger 162 is provided on the end of the detent and this has a beveled side edge 163 and is provided for the purpose of pulling the detent into a locked position by the lock in the outer knob through engagement of the cam surface 134 with the finger 135 which is connected in the assembly illustrated in Fig. 19 to the lock in the outer knob.

A trigger designated generally 164 (note particularly Figs. 17 and 18) is formed of a bar having a pivoting corner 165 by which it

- is pivoted to the hub 166 of the end plate 167. This detent is made in the form of a bell crank having a short arm 168 with a nub 169 thereon for pressing the bell crank in one direction 5 by the pressure of cam 136 of the finger 135 of the block 133. The shank 170 of this trigger is provided with an offset finger 171 which engages in the notch 160 of the detent 156 and holds this trigger in its bolt locking position. 10 A releasing nub 172 is provided on the end of the shank of the trigger and extends through the hub 174 of the end plate opposite to the end plate 167 and this is adapted to be engaged by the lug 152 on the rotatable sleeve 150. A compression spring 173 is seated in the hub 166 and bears against the arm 168. 15
- The operation of locking and unlocking the lock is as follows:
- In Figs. 9 and 10 the lock is illustrated in its unlocked position and in order to lock this by the outside door knob lock said lock is operated by a key so that the cam 134 on the finger 135 engages the finger 162 on the detent and draws this detent partly through the crosshead of the lock and brings the finger 161 into engagement with the notch 144 of the crosshead. This locks the crosshead from movement with the latch bolt in its locked position and at the same time the finger 171 20 of the trigger 164 slips into the notch 160 of the detent and holds the detent in its locking position. In order to unlock this from the outside door knob lock the direction of rotation of the cam finger 135 is reversed so that the finger 162 is released and the cam surface 136 bears on the nub 169 of the trigger, forcing the finger 171 out of the notch 160 and allowing the compression spring 158 to retract the detent, thus releasing the crosshead for 25 sliding movement, which crosshead may be turned by either knob due to the engagement of the pins of the disks engaging the side pieces 30 on the crosshead, these disks being secured to the doorknob shanks.
- In order to lock the latch bolt from the inside knob the finger button 144' is turned, the action of the driving cam 148 having the screw surface 149 forcing the driven cam 153 inwardly, and as the detent 156 is connected to this driven cam the detent is shifted into the locking position. The spring 158, which is a combined torsion and compression spring, maintains the driven cam pressed against the driving cam and tends to rotate the sleeve 150. The block 147 is provided with a transverse tongue 175 engaging the lugs 176 in the sleeve 150 and rotating this sleeve, the tongue also fitting in the notch 175' in the cam block 148. However, to unlock the lock it is necessary to release the trigger which has the finger 171 engaged in the notch 160 of the detent, and this is accomplished by rotating the finger knob 144' in a reverse direction from the locking action which brings the cam face on the lug 152 of the sleeve 150 into en-

gagement with the releasing nub 172 on the end of the detent and this swings the trigger inwardly and disengages the finger 171 from the notch 160, allowing the compression spring 158 to act in retracting the detent 70 from engagement with the notch 144 in the crosshead. By this construction it will be seen that without rotating the detent I give this a longitudinal motion both in the locking and unlocking by the lock in the outside knob and also by the operation of the finger button on the inside knob. Manifestly, when the crosshead is locked in position either knob is ineffective to give this a sliding motion and hence to operate the latch bolt. However, when the detent is in its unlocked position and the crosshead is free to move, the rotation of either knob in either direction will withdraw the latch bolt. It will be noted that the finger turning device including the block 85 147 and the cam block 148 may be rotated part of a circle until the tongue 175 engages the lugs 176 on the sleeve and this allows thrusting the detent into the locking position without rotation of the sleeve but on the reverse rotation the sleeve is turned, the face 177 of the cam lug 152 engaging the releasing nub 172. A stop pin 178 is provided in the hub 174 to engage the face 179 of the lug 152 and limit the rotation of the sleeve. 90

Various changes may be made in the details of construction without departing from the spirit or scope of the invention as defined by the appended claims.

I claim:

1. A door knob lock having a latch bolt, a knob, means interconnecting the knob and the bolt to actuate said bolt, a finger operated rotatable device in the knob, a slidable detent, an interconnecting means between said rotatable device and the detent to slide said detent, and means interconnecting the detent and the latch bolt to lock the latch bolt in one position or in another position of the detent to release the latch bolt for movement by the knob, a trigger operatively connected with the detent, means to move said trigger to engage the detent and hold the detent in a locking position, and means operative by the rotatable device to release the trigger 115 from the detent to permit shifting of the detent to its unlocking position.

2. A door knob lock having a slidable crosshead with a latch bolt connected thereto, a rotatable knob, means interconnecting between the knob and crosshead to slide such crosshead, a finger operated rotatable device mounted in the knob, a slidable detent, means interconnecting said rotatable device and the detent and to slide such detent from an unlocking to a locked position, means in the locked position engaging the detent and the crosshead, and a pivotally mounted trigger having means to engage the detent and restrain same in its locking position.

3. A door knob lock as claimed in claim 2, means actuated by rotation of the finger button to operate the trigger for release of the detent, and means to return the detent to its 5 inoperative or unlocking position.

4. A door knob lock as claimed in claim 2, an outer knob having a rotatable lock therein, and means operated by said lock to move the detent longitudinally from its unlocked 10 to its locking position, said means being operative on a reverse motion to release the trigger for release of said detent.

5. A door knob lock having a slidable latch bolt, an inner and an outer knob, means interconnecting between said knobs and the latch bolt to reciprocate said bolt, a slidable detent operative from a position to permit movement of the bolt to a position restraining such movement, a rotatable finger grip device 20 axially mounted in the inner knob, means interconnecting said device and the detent to shift such detent longitudinally from its unlocked to its locked position, and a lock in the outer knob having a rotatable means to engage 25 the detent to move such detent from its unlocked to its locking position, a trigger to engage the detent in its locked position and restrain it in such position, means operatively connected to the rotatable device in the 30 inner knob on a reverse rotation to operate the trigger to release same from the detent, means to return the detent to its unlocked position, and means connected to the lock in the outer knob to actuate the trigger to release the detent for movement of such detent 35 from its locked to its unlocked position.

6. A door knob lock having a slidable latch, an inner knob having a shank with means to operate said latch, a slidable locking detent 40 to lock the latch in its locking position, a driven cam connected to said detent, a finger operated rotatable device mounted axially in the knob and having a driving cam connected thereto, said driving cam in its rotation of 45 movement communicating a longitudinal movement to the driven cam and to the detent, the detent in one position locking the latch bolt and in another position releasing the latch bolt for movement, a rotatable sleeve 50 mounted in the shank of the knob, a trigger having means to hold the detent in its locked position, means on the rotatable device to rotate the sleeve, said sleeve having means interacting with the trigger to release the trigger 55 from the detent, and a spring means to return the detent to its normal unlocked position.

7. A door knob lock as claimed in claim 6, an outside knob having a shank, a lock having a rotatable barrel in such knob, a cam lock having a finger with a pulling and a pushing cam thereon, there being a finger on the detent engageable by the pulling cam to pull said detent into a locking position, the 65 trigger having a nub engaged by the pushing

cam to release the trigger from the detent for unlocking the latch bolt.

8. In a door knob lock, a slidable cross-head having an outer and an inner member, the outer member having a top plate and two side arms, the inner member having a bottom plate and two strips fitting inside of the side arms and having two side pieces, the side arms of the strips being connected by the inwardly bent ends on the side arms engaging the strips. 70

9. In a door knob lock, a sleeve adapted to fit in the opening of a door and having a pair of side plates rigidly connected thereto, each side piece having a hub with a central opening and an arcuate slot concentric therewith, each plate having a guide, such guide having a pair of in-turned flanges adjacent an opening in the plate. 75

10. In a door knob lock, an inner knob having a shank, a finger operated rotatable device centrally mounted in the knob and operative through the center of the shank, a driving cam connected to said device and having a screw-shaped cam formed on its inner end and extending axially, a driven cam having an axially projecting finger on its outer end to bear against the cam surface, a detent connected to the driven cam, and a compression spring forcing the driven cam into engagement with the driving cam. 85

11. In a door knob lock as claimed in claim 10, the shank of the knob containing a rotatable sleeve, such sleeve surrounding the driving and the driven cams, a pivotally mounted trigger having means to engage the 100 detent and to hold same in its locking position, means having a lost motion to rotate said sleeve, and a cam lug on the sleeve to release the trigger from the detent.

12. A door knob lock having an outer knob with a lock therein, an inner knob with a rotatable finger button, a thrusting cam operatively connected to be actuated by the button, a pulling cam operatively connected to be actuated by the lock, a slidably mounted detent actuated in one direction by the thrusting cam, and in the same direction by the pulling cam, a latch bolt, means to lock said bolt by the detent when moved longitudinally by either of the cams, a spring to return the detent to its original position, and a trigger to release the detent, such trigger being operated by either the lock and the outer knob or the rotatable button. 105

13. A door knob lock as claimed in claim 12, the trigger being pivotally mounted and having means to interengage with the detent to retain same in a position for locking the bolt, the pulling cam having a thrusting cam surface thereon to release the trigger. 110

14. A door knob lock as claimed in claim 12, the trigger having means to engage the detent to retain same in a position for locking the bolt, a rotatable sleeve operatively connected to be actuated by the rotatable button, 115 125 130

and means on said sleeve to actuate the trigger to release the detent.

15. A door knob lock as claimed in claim 12, an end plate mounted adjacent the outer knob and having a trigger pivotally mounted therein, said trigger having means to interconnect with the detent to hold such detent in a position for locking the bolt, a spring in such end plate normally pressing the trigger into its engaging position with the detent, the pulling cam having an end cam surface to engage the trigger to release same from the detent, a rotatable sleeve surrounding the thrusting cam adjacent the inner knob and having means to engage the trigger to release same on partial rotation of the finger button.
16. A door knob lock having a fixed sleeve, a fixed guide plate at each end of the sleeve, means to retain the sleeve in a lock opening in a door, a crosshead slidably mounted in said guide plates and having a latching bolt connected thereto, an outer knob having a shank operatively connected with one of the guide plates, an inner knob having a shank operatively connected with the other guide plate, means actuated by either knob and its shank to slide the crosshead and the latching bolt, a rotatable finger button in the inner knob, a driving thrust cam connected thereto, a driven cam actuated by the driving cam and having a longitudinally extending detent connected thereto, said detent extending through the guide plates through the crosshead and having means in one position of movement of the detent to engage the crosshead to retain the bolt in its locked position, a pivotally mounted trigger with a spring normally actuating same into latching position with the detent, a rotatable sleeve in the shank of the inner knob and actuated by the finger button to release the trigger from the detent, and a spring to return the detent to its original position and permit movement of the bolt by either knob.
17. A door knob lock as claimed in claim 16, a lock operatively connected to the outer knob and having a pulling cam connected to such lock, means for interconnecting the pulling cam and the detent to slide such detent into its latched position with the crosshead to lock the bolt, said pulling cam having a second cam surface to engage the trigger and to release the trigger from the detent.
18. In a door knob lock, a fixed sleeve with a pair of fixed guide plates at each end, and means to mount said sleeve with the plates in an opening in a door, a crosshead slidably mounted in the guide plates and having a latch bolt connected thereto, an outer knob with a shank, an inner knob with a shank, and means to mount said knobs to operate in relation to the guide plates to shift the crosshead by the rotation of either knob for unlatching the door, a slidably mounted detent extending from one shank to the other

through the crosshead and having means for interengaging with the crosshead in one position to retain the crosshead with the bolt in its locked position and in another position to permit sliding of the crosshead and bolt, a lock in the outer knob having a pulling cam with means interengaging said cam and the detent to pull the detent into its latching position with the crosshead, a pivotally mounted trigger, the pulling cam having a second cam surface for engaging with the trigger to release the trigger, said trigger having means for interconnecting with the detent to hold same in its latching position, and a spring operating on the detent when released by the trigger to return the detent to its original position for free movement of the cross head and bolt by either knob.

19. In a door knob lock as claimed in claim 18 the inner knob having a rotatable finger button with a thrusting driving cam connected thereto, a driven cam axially mounted in the sleeve and connected to the detent to shift the detent into its latching position on rotation of said button in one direction, a sleeve rotatably mounted in the inner shank and surrounding the driving and driven cams, said sleeve being actuated in one direction of rotation by said button, and said sleeve having means for releasing the trigger from its latching position with the detent, the spring for returning the detent being mounted in said sleeve.

20. In a door knob lock as claimed in claim 18, the inner knob having a rotatable finger button therein with a thrusting driving cam connected thereto, the shank of the inner knob having a driven cam therein connected to the detent, said detent having a lateral projecting finger to engage the crosshead and having a notch to be engaged by the trigger, and an end finger to be engaged by the pulling cam, said trigger being pivoted in the guide plate adjacent the outer knob and having an opposite finger to engage in the knob of the detent, a laterally extending arm to be engaged by the second cam on the pulling cam, said trigger having a releasing nub at its opposite end, a sleeve rotatably mounted in the shank of the inner knob and surrounding the driving and driven cams, said sleeve being rotated by the finger button in one direction, and means on the sleeve to engage the nub of the trigger to shift the trigger into releasing position.

21. In a door knob lock, a slidably mounted crosshead adapted for installing in a door having a latch bolt connected thereto, an inner knob having an inner shank at one side of the door and operatively connected to actuate the crosshead and the bolt, a rotatable finger button in the knob, a thrusting driving cam having an axial cam on its inner end rotatable by the button, a slidably mounted driven cam having an axial finger to en-

gage the driving cam, a slidably mounted 5
detent connected to the driven cam and ex-
tending from the crosshead and having a
latching means for interconnecting with the
cross head to latch the crosshead with the
bolt in its locked position, a spring means for
returning the detent to its original unlatched
position, a pivotally mounted trigger moving
transverse to the detent and having
10 means for latching the detent in its latching
position with the crosshead, a rotatable sleeve
in the inner shank and surrounding the driv-
ing and driven cams, said spring being con-
nected to said sleeve, means to interengage
15 the finger button and said sleeve to rotate the
sleeve in one direction, and means on said
sleeve to engage and release the trigger from
its latching position with the detent, and a
spring for normally urging the trigger into
20 such latched position.

22. In a door knob lock, a slidable cross-
head having a latch bolt connected thereto,
and means for mounting the crosshead and
the bolt in a door, an outer knob having a
25 shank operatively mounted to slide the cross-
head and the bolt, a lock in said shank having
a pulling cam extending in axial direc-
tion in the shank, a slidably mounted de-
tent extending through the crosshead from
30 side to side and having an end finger to be
engaged by the pulling cam to shift the de-
tent into latching relation with the crosshead
to latch the bolt in the locked position, a
spring normally urging the detent into its
35 unlatching position, a pivotally mounted
trigger having means for engaging the de-
tent to latch same in the latching position
of the detent with the spring normally urging
the trigger into such position, the pulling
40 cam having a second cam surface to engage
an arm on the trigger and shift the trigger
into a releasing position as regards the de-
tent to permit return of the detent to its
original unlatching position.

45 23. In a door knob lock, a sleeve, a guide
plate secured at each end of the sleeve, each
having an arcuate opening therein and guide
flanges, means to retain this sleeve with the
guide plates in an opening in a door, a cross-
50 head slidably mounted in the guide flanges,
knobs on opposite sides of the guide plates
and having means extending through the
slots to operate the crosshead, and a latch
bolt connected to such crosshead.

55 24. In a door knob lock, a main sleeve hav-
ing a guide plate at each end, each guide plate
having guide flanges and an arcuate open-
ing with a hub having a central opening, a
crosshead slidably mounted in the guide
60 flanges, a second sleeve secured to and ex-
tending radially from the main sleeve, a
latch bolt operating in the second sleeve
and connected to the crosshead, said second
sleeve being adapted to prevent rotation of
65 the main sleeve in a door opening, means

adapted for securing the main sleeve in a
door opening, a pair of knobs each having
means extending through one of the slots
to actuate the crosshead, and a latching
means for the crosshead extending through
70 the hubs of the guide plates.

25. In a door knob lock as claimed in claim
24, each knob having a shank, there being
an outer knob with a rosette connected to
the main sleeve and adapted to engage one
75 side of the door, an end piece secured to the
opposite end of the sleeve, a knob shank
sleeve mounted on a shank connected to the
inner knob and having means to interconnect
80 with the end piece and retain the inner knob
and shank on the main sleeve, and a rosette
secured to the knob shank sleeve and en-
gaging the opposite face of the door.

26. In a door knob lock, a main sleeve hav-
ing a guide plate secured thereto at each
end with a crosshead slidable in the guide
plates, such crosshead having a latch bolt
connected thereto, an outer knob having a
85 shank with a rosette connected to one end of
the sleeve and adapted to bear against one
face of a door, the sleeve fitting in an opening
in such door, an inner knob having a shank
with a shank sleeve surrounding the shank
90 of the knob, an end piece secured to the
opposite end of the sleeve having means to
interconnect the shank sleeve and the end
piece and thereby retain the inner knob and
shank operatively connected to said sleeve,
95 and means actuated by either knob to ac-
tuate the crosshead and bolt.

27. In a door knob lock as claimed in claim
26, the connection between the end piece and
the knob shank sleeve comprising angle
100 lugs with a spring on the end piece, the
shank sleeve having projecting fingers en-
gaging with the spring and said lugs, and an
ornamental rosette engaging said shank
sleeve and one face of the door.

28. In a door knob lock as claimed in claim
26, each guide plate having a central hub with
an opening extending therethrough, a move-
able detent extending through the hub and
the crosshead, and means operatively con-
nected to both of the knobs to actuate the de-
tent, said detent and crosshead having means
110 for interconnection to latch and thereby pre-
vent movement of the crosshead when the
latch bolt is in its locked position.

29. In a door knob lock, a slidably mounted
crosshead with a latch bolt connected thereto
and adapted for inserting in an opening in
a door, an inner knob having a rotatable
finger button, an outer knob having a lock,
a rotatable detent operatively connected to
the finger button and to the lock to be ro-
tated on its axis by either the finger button
or lock in a forward and reverse direction,
said detent in one position interengaging
with the crosshead and latching the crosshead
with the bolt in its locking position.

30. In a door knob lock, a main sleeve having guide plates at each end, means to secure the sleeve in a door opening, a crosshead slidably mounted in the guide plates and having a latch bolt, inner and outer knobs operatively connected to said sleeve and each having means to reciprocate the crosshead and hence the bolt, a detent extending axially through the sleeve and being in axial alignment with the knobs, a rotatable finger button in the inner knob with a connection to one end of the detent, a lock in the outer knob having means with a lost motion connection to the opposite end of the detent, said detent being rotatable by either the button or the lock, said detent having a lateral projecting finger to engage the crosshead in one position and latch such crosshead with the bolt in its locked position, or in another position to permit reciprocation of the crosshead and bolt.
31. In a door knob lock, a cylindrical main sleeve having a guide plate connected thereto at each end, each plate having a tubular central hub and an arcuate slot and guide flanges, a crosshead mounted in the guide flanges for reciprocation transverse to the sleeve, a latch bolt connected to the crosshead, an inner and outer knob each having shanks with means for operatively mounting the shanks on the sleeve to permit rotation of the shanks, means connected to said shank and extending through the slots for reciprocating the crosshead and hence the bolt, a rotatable detent extending through the sleeve, the hubs, and into both shanks, a rotatable finger button in the inner knob having a lost motion connection to one end of the detent, a lock in the outer knob and having a lost motion connection to the other end of the detent, whereby the detent may be rotated by either knob and in a forward and reverse direction, and means to interconnect the detent and the crosshead when the latch bolt is in its locked position and in another position of the detent to permit movement of the crosshead.
32. In a door knob lock as claimed in claim 31, a secondary sleeve connected to the main sleeve and forming a mounting for the bolt, said second sleeve being adapted to fit in a second opening in a door radial to the opening having the main sleeve.
33. In a door knob lock as claimed in claim 31, the outer knob shank having a rosette mounted thereon and connected to the main sleeve, an end piece connected to the opposite end of the main sleeve, the inner knob shank having a sleeve thereon with means interconnecting between said latter sleeve and the end piece, said rosette retaining the outer knob and shank in operative relation to the main sleeve, said end piece and sleeve on the inner shank retaining such inner shank and inner knob in operative relation to the main sleeve, and an ornamental rosette operatively connected to the sleeve on the

inner shank and adapted to engage the side of the door opposite the first mentioned rosette, said rosettes being operative to retain the main sleeve in an opening in a door.

In testimony whereof I have signed my name to this specification.

HENRY L. ARSTE.
